CLAIM

The ornamental design for a cargo container indicator, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a front, top, and right side perspective view the cargo container, showing the new design wherein the indicator of the cargo container is illuminated with low intensity green light;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a front, top, and right side perspective view the cargo container, showing the new design wherein the indicator of the cargo container is illuminated with medium intensity green light;

FIG. 9 is a front elevational view thereof;

FIG. 10 is a rear elevational view thereof;

FIG. 11 is a left elevational view thereof;

FIG. 12 is a right elevational view thereof;

FIG. 13 is a top plan view thereof;

FIG. 14 is a bottom plan view thereof;

FIG. 15 is a front, top, and right side perspective view the cargo container, showing the new design wherein the indicator of the cargo container is illuminated with high intensity green light;

FIG. 16 is a front elevational view thereof;

FIG. 17 is a rear elevational view thereof;

FIG. 18 is a left elevational view thereof;

FIG. 19 is a right elevational view thereof;

FIG. 20 is a top plan view thereof;

FIG. 21 is a bottom plan view thereof;

FIG. 22 is a front, top, and right side perspective view the cargo container, showing the new design wherein the indicator of the cargo container is illuminated with a shade of orange light;

FIG. 23 is a front elevational view thereof;

FIG. 24 is a rear elevational view thereof;

FIG. 25 is a left elevational view thereof;

FIG. 26 is a right elevational view thereof;

FIG. 27 is a top plan view thereof;

FIG. 28 is a bottom plan view thereof;

FIG. 29 is a front, top, and right side perspective view the cargo container, showing the new design wherein the indicator of the cargo container is illuminated with a shade of red light;

FIG. 30 is a front elevational view thereof;

FIG. 31 is a rear elevational view thereof;

FIG. 32 is a left elevational view thereof;

FIG. 33 is a right elevational view thereof;

FIG. 34 is a top plan view thereof; and,

FIG. 35 is a bottom plan view thereof.

Figs. 1-35 are executed in color to convey only the differing colored appearances of the regions of these figures which have colored shading. No particular coloration(s) are claimed for the remaining portions of the claimed design in these figures.

The ornamental design which is claimed is shown in solid lines in the drawings. Any broken lines in the drawings illustrate portions of the cargo container which form no part of the claimed design.
